UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

JACQUARD INDICATOR FOR BOX LOOMS.

Application filed June 17, 1926. Serial No. 116,750.

This invention relates to improvements in jacquard indicators for box looms and it is the principal object of the invention to render mechanisms of this type positive in their movements by a direct connection from the jacquard which insures correct timing of the box motion.

My invention is more particularly an improvement on the type of motion shown in patent to Ryon No. 1,554,297. In that motion there is shown a plurality of horizontally movable slides each supported in part by a pin which passes through a downwardly curved slot. Cord connections from the jacquard move the slide so that the pin will lie either in the right or left hand end of the curved slot. It has been found in practice that the type of slot shown in said patent does not require the slide to move positively to complete an indicating movement.

When a loom is stopped for any reason with the indication half given to the indicator it is found that the slide will rest on the pin at a point intermediate the ends of the slot and the result of this is that the hooked links which cooperate with the regularly moving actuator both lie in the path of the latter and either cramp or break the motion. It is a further object of my invention to prevent this uncertainty of movement of the indicating member by providing a series of detents to cooperate with the members moved by the jacquard.

It has further been found that the actual movement of the controlling part of the box motion which determines which of the shuttles shall become active varies in amount with different types of box motions and it is a further object of my invention to render the motion applicable to all styles of box motions by providing an adjustable connection between the actuated lever of the indicating mechanism and the box controlling devices.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a side elevation of a loom having my invention applied thereto,

Fig. 2 is an enlarged side elevation of the motion, parts being removed,

Fig. 3 is a top plan view looking in the direction of arrow 3, Fig. 2, and

Fig. 4 is a fragmentary vertical section through one of the vibrator lifting levers.

Referring to the drawings it will be seen that I have provided a loomside 10 having secured thereto a box motion stand 11 provided with a heel pin 12 on which is mounted a plurality of so-called vibrator levers 13. Each vibrator has a vibrator gear 14 rotatably mounted thereon as at 15 and each gear is provided with a connector 16. The forward end of each connector is attached to one or another of a set of bell crank levers 17 and 18 which work in pairs and are connected by links 19 to a floating box lever 20. The lever is operatively connected to a box rod 21 on the upper end of which is mounted a series of shuttle boxes indicated at 22.

Constantly but oppositely rotating cylinder gears 23 and 24, driven in any approved manner, are located one above and the other below the vibrator gears 14 and are each provided with gear teeth to engage and rotate the vibrator gears 14, depending upon the vertical position of the vibrator lever 13. The matter thus far described is of common construction and is the usual well-known side plate box motion such as that shown in Patent No. 551,104.

The mechanism for controlling the vertical position of the vibrator levers 13 comprises a stand 30 bolted or otherwise secured to the loom frame and having a depending foot 31 on which is pivoted as at 32 a cam lever 33 having a roll 34 thereon. Said roll cooperates with a cam 35 secured to the top shaft 36' of the loom and makes a complete revolution each pick of the loom. An actuator lever 36 is pivoted as at 37 to the stand 30 and is operatively connected to the cam lever by an adjustable link 38 as indicated in Fig. 1.

A stud 39 is secured to and extends laterally from the frame 30 and has mounted thereon for rocking movement a plurality of three-armed levers 40 which as indicated

more particularly in Fig. 2 are each provided with forwardly and rearwardly extending substantially horizontal arms 41 and 42 and provided also with an upstanding 5 arm 43 having a rounded upper surface. A pin 44 secured to the frame 30 has pivotally mounted thereon a plurality of lifting levers 45, one for each of the levers 40. Each lifting lever is provided with a run 46 terminating in forward and rearward notches 47 and 48, respectively, positioned to receive the upper rounded end of arm 43. Each lever 40 has pivotally connected thereto a pair of lifting hooks 49 and 50 each provided 10 with a notch 51 and an upwardly extending guide 52.

The matter thus far described as being supported on stand 30 is substantially the same as that set forth in the aforesaid patent to Ryon, the cam 35 causing a vertical reciprocation of actuator lever 36 to raise a lifting knife 53 each pick of the loom to engage the notches 51 of whichever hooks have been moved into the path of the knife 53. 20 As the hooks are lifted the corresponding levers 40 will be rocked on pin 39 to cause a change in the vertical position of the vibrator lifting levers 45, the result of which is to change the relation of the associated 25 vibrator gear 14 in regard to the actuating cylinders 23 and 24.

My improvements relate more particularly to the means for changing the position of the hooks 49 and 50 and also for establishing operative connections between the vibrator lifting levers 45 and the vibrator levers 13. Accordingly, I provide the stand 30 with a horn 60 provided with a stud 61 on which is pivotally mounted a plurality of 30 controller levers 62 each provided with spaced fingers 63 between which the guides 52 may extend. Each controller lever 62 is provided with an upper arm 64 connected above the stud 61 to a flexible cord 65 actuated by a jacquard hook 66 and each lever 62 is further connected below the stud 61 to a second flexible connector 67 attached to another jacquard hook 68.

Horn 60 is provided with a pair of laterally extending arms 69 and 70 which guide a plurality of spring plungers or detents 71, each plunger having a head 72 sliding in arm 70 and receiving the thrust of a compression spring 73 the rear portion of which presses against arm 69. Each head is formed as a detent to enter one or another of a plurality of notches 74 formed in the rear end of a horizontal arm 75 cast integral with the corresponding controller lever 62. 50

It is to be understood that the cards of the jacquard will be so punched that but one of the pair of hooks 66 or 68 which is associated with each controller lever 62 will be raised on any given pick, the upward 60 movement of the selected hook causing an

oscillating movement of the corresponding controller lever 62 on stud 61 to move the hooks 49 and 50 with respect to the knife edge 53. The detents or plungers serve to complete any oscillating movement of the controller levers which may have been started but not completed by the jacks 66 and 68. If the loom should stop, for instance, before the jacquard has moved the controller levers 62 for half of their throw the plungers 70 would act to return said controller levers to their original position should the weight of the lingoies move the lay backwardly to create a slight reverse motion of the loom. On the other hand, should the loom stop shortly after the controller levers have passed their mid-position the plungers would be effective to move said levers completely to their new position. For this reason there is no uncertainty as to the position of the hooks 49 and 50 and the latter will always be properly positioned with respect to the knife edge 53. 75

In order that the rocking movement of the three-armed levers 40 may have operative connection with the vibrator levers 13 I provide each of the lifter levers 45 with a special form of stud shown more particularly in Fig. 4 and indicated at 76, said stud having a shank 77 which is received in the forwardly extending end of the corresponding lifter lever 45. The stud is provided with a shoulder 78 and a bearing portion 79 which receives the upper end of a wire or other convenient link 80 the lower end of which as indicated in Fig. 1 is connected to one 100 of the vibrator levers 13. A set screw 81 threaded into each lifter lever 45 serves to position the stud 76 and affords an adjustment of the upper end of the link 80 from or toward the pivotal support 44 to increase 105 or diminish the throw of said links 80.

From the foregoing it will be seen that I have provided a simple means for rendering definite the action of lever 62 and thereby controlling the hooks 49 and 50 so that the same will always be properly positioned with respect to the knife edge 53. It will further be seen that each of the lifter levers 45 is provided with means for rendering the same capable of giving more or less throw 110 to the links 80.

Having thus described my invention it will be apparent that changes and modifications may be made therein by those skilled in the art without departing from the spirit and scope of the invention, and I do not wish to be limited to the details herein disclosed but what I claim is:

1. In a jacquard box indicating mechanism for looms, a box motion, a regularly moving actuator, a lifter lever operatively connected to the box motion to control the action thereof, a pair of hook members associated with each lifter lever, a controller to operate on both of said hook members at the 125

same time and move a portion of each of said hook members in the same direction, and means operatively connected to the control member to insure the complete movement thereof in either direction.

2. In a jacquard box indicating mechanism for looms, a box motion, a lifting lever for the box motion operatively connected thereto to effect a change in the box motion

10 when the lever is moved, a regularly moving actuator, a pair of members each capable of movement into operative relationship with respect to the actuator and each operatively connected to the lifting lever so that when

15 one of said members is lifted the lifting lever will move in one direction and when the other of said members is lifted the lifting lever will move in another direction, a controller for the members operatively connected to the jacquard and movable thereby, and means effective to move the controller toward one or the other of the limits of movement thereof should the same fail to receive a complete movement from the jac-

20 quard.

3. In a jacquard box indicating mechanism for looms, a box motion, a lifting lever for the box motion operatively connected thereto to effect a change in the box motion

25 when the lever is moved, a regularly moving actuator, a pair of members each capable of movement into operative relationship with respect to the actuator and each operatively connected to the lifting lever so that when

30 one of said members is lifted the lifting lever will move in one direction and when the other of said members is lifted the lifting lever will move in another direction, a pivotally mounted controller lever for the mem-

35 bers operatively connected to the jacquard on opposite sides of the pivot thereof and movable thereby, and means effective to move the controller lever toward one or the other of the limits of movement thereof

40 should the same fail to receive a complete movement from the jacquard.

4. In a jacquard box indicating mechanism for looms, a box motion, a lifting lever for the box motion operatively connected thereto to effect a change in the box motion 50 when the lever is moved, a regularly moving actuator, a pair of members each capable of movement into operative relationship with respect to the actuator and each operatively connected to the lifting lever so that when one of said members is lifted the lifting lever will move in one direction and when the other of said members is lifted the lifting lever will move in another direction, a controller for the members operatively connected to the jacquard and movable thereby, and means effective to move the controller toward one or the other of the limits of movement thereof should the same fail to receive a complete movement from the jac- 55 quard, said means including a detent and a notched element cooperating therewith and operatively related to the controller.

5. In a jacquard indicator for box looms, a box motion, a lifting lever operatively connected thereto to effect a change in the operation of the box motion when said lever is moved, a three-armed lever one of the arms of which is operatively connected to the lifting lever, a lifting hook pivoted on each 70 of the other arms of the three-armed lever, one of said hooks when raised being effective to move the lifting lever in one direction and said lifting lever moving in the other direction when the other hook is raised, a regularly moving actuator for the hooks, a controller lever operatively related to both the hooks to move the same angularly, jacquard mechanism to move said lever positively in opposite directions, and means operatively 75 associated with the controller to complete any movement of the controller which is initiated but not completed by the jacquard mechanism.

In testimony whereof I have hereunto 80 affixed my signature.

ELBRIDGE R. HOLMES.
